(57) **CLAIM**

The ornamental design for a bidirectional bone conduction tactical communication system, as shown and described.

DESCRIPTION

FIG. 1 is a perspective view of a bidirectional bone conduction tactical communication system showing our new design;

FIG. 2 is a front view of set 1 thereof;

FIG. 3 is a back view of set 1 thereof;

FIG. 4 is a top view of set 1 thereof;

FIG. 5 is a bottom view of set 1 thereof;

FIG. 6 is a left side view of set 1 thereof;

FIG. 7 is a right side view of set 1 thereof;

FIG. 8 is a perspective view of an intercom remote control module (set 2) of a bidirectional bone conduction tactical communication system shown separately for purposes of illustration;

FIG. 9 is a front view of set 2 thereof;

FIG. 10 is a back view of set 2 thereof;

FIG. 11 is a top view of set 2 thereof;

FIG. 12 is a bottom view of set 2 thereof;

FIG. 13 is a left view of set 2 thereof;

FIG. 14 is a right view of set 2 thereof;

FIG. 15 is a perspective view of an intercom control (set 3) of a bidirectional bone conduction tactical communication system shown separately for purposes of illustration;

FIG. 16 is a front view of set 3 thereof;

FIG. 17 is a back view of set 3 thereof;

FIG. 18 is a top view of set 3 thereof;

FIG. 19 is a bottom view of set 3 thereof;

FIG. 20 is a left view of set 3 thereof; and,

FIG. 21 is a right view of set 3 thereof.

The claimed bidirectional bone conduction tactical communication system as set forth in the following specification, comprising 3 sets: a bone conduction headset (set 1), an intercom remote control module (set 2), and an intercom control part (set 3).
